GLOVE DRIER

Alexander Ross, Flushing, N. Y.

Application May 17, 1954, Serial No. 30,520

Term of patent 14 years

(Cl. D80—8)

FIG. 1.

FIG. 2.

FIG. 3.

Fig. 1 is a plan view of a glove drier, showing my new design;

Fig. 2 is a section taken along lines 2—2 of Fig. 1; and

Fig. 3 is a section taken along lines 3—3 of Fig. 1.

The characteristic features of my design reside in the grill work in the digit area of the glove drier.

I claim:

The ornamental design for a glove drier, as shown and described.
